UNITED STATES PATENT OFFICE

2,560,372

AIR CONDITIONING DEVICE

Jose Sanchis, Newark, N. J.

Application August 3, 1945, Serial No. 608,670

1 Claim. (Cl. 257—137)

1.

This invention relates to air conditioning and cooling devices, and has for one of its main objects the provision of a simple, inexpensive device of this nature which is specially adapted for use in the home.

Another object of the invention is the provision of an air conditioning and cooling device in which no refrigerants are used, and which may be hung on a wall or otherwise supported.

A further object of the invention is the provision of a device of this character in which air is drawn from the outside into a chamber and then preferably expelled by means of a fan through the interstices of an automobile honeycomb-type radiator in which a continuous water circulation is maintained.

Still another object of the invention is the provision of such a device in which the cooled air currents may be directed in any desired direction.

Other objects and advantages will appear as the nature of the improvements is better understood, the invention consisting substantially in the novel arrangement and co-relation of parts herein fully described, and illustrated in the accompanying drawings, wherein similar reference characters are used to denote corresponding parts throughout the several views, and then finally pointed out and specifically defined and indicated in the appended claim.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

In carrying out a preferred embodiment of the invention, it was found advantageous to employ a honeycomb type automobile radiator in which a continuous circulation of water is maintained. Directly to the rear of the radiator there is provided a chamber in which a motor draws air from the exterior through a pipe or conduit in communication with the interior of said chamber, the air is then driven through the honeycomb openings in the radiator.

In a second embodiment of the invention, a fan draws air into a chamber from which it is expelled through a conical opening and spaces between the pipes or tubes of a special type radiator. In this latter form of the invention a type of Venetian-blind arrangement may be provided for directing the cooled air in the desired direction.

2.

In the drawings:

Figure 1 is a perspective view showing a preferred form of the invention;

Figure 2 is a sectional view taken on line 2—2, Figure 1;

Figure 3 is a cross sectional view through a modified form of the invention;

Figure 4 is a perspective view of the improved type radiator used;

Figure 5 is a rear view looking from the right of Fig. 3; and

Figure 6 is a front view of the device.

Referring now to Figures 1 and 2 of the drawings, 10 indicates a radiator which comprises a lower water tank 11 and upper water tank 12 and the intermediate tank connecting section 13, said section comprising pipes or tubes 14 criss-crossed in honeycomb fashion to provide openings or air passages 15.

20 In order to maintain a continuous circulation of water through the radiator, the lower tank 11 is connected by a hose 16 to a water tap or faucet 17 and the upper tank 12 has a discharge or overflow pipe 18 leading therefrom to a sink 19 or bowl 19. If desirable, the upper tank 12 may be provided with a respiration or vent tube 20.

Directly behind the radiator 10 there is provided a box 21 having an air or ventilating chamber 22, said chamber being in communication with the exterior atmosphere by means of a pipe or conduit 23. Said conduit may extend outwardly through a window frame 24.

Air is drawn into the chamber 22 by means of a motor driven fan 25 which also expels the 35 air into the room in which the device is placed through the openings 15 between the water tubes 14. In practice the faucet 17 is opened and water will flow into the radiator through the pipe or hose 16. When the radiator is full water 40 will continue to flow out of the top or upper tank 12 through the pipe 18, thus producing a continuous water circulation within the radiator.

As the air flows out of the openings 15 it will, due to the large cooling area of the honeycomb tube arrangement, become thoroughly cooled 45 without the aid of any artificial or other refrigeration means.

In Figs. 3 to 6 there is shown a modified form of the invention. In this form of the invention 50 the air box 30 may be supported on a wall in line with a window or other opening 31. Contained within the box 30 and suitably supported therein by means of a strap 32 is a motor driven fan 33. A cooling compartment 34 is formed by 55 the walls of a box 35 which forms a continuation

of the air box 30 and is divided therefrom by a wall 36 having a central opening 37.

Suitably supported within the chamber 34 is a water radiator 38 which comprises a tube or pipe frame 39 and a series of pipes 40 inter-connecting with the frame 39. A helical frusto-conical coil 41 is connected at one end thereof to the frame at 42. The opposite end of the coil 41 terminates in a depending pipe portion 43 which forms a water outlet. A pipe 44 connected to the frame 39 forms a water inlet to the radiator.

In practice, the pipe 44 which is the counterpart of the hose or pipe 16 is connected to a water supply, which when opened, causes water to circulate through the radiator and out of the outlet pipe 43, thus creating a continuous water circulation through the radiator.

As air is drawn in from the outside through the opening 31, it passes around the coil and frame pipes and is thoroughly cooled thereby. If desirable, a Venetian blind arrangement 45 may be provided at the front of the radiator 38 to direct the current of cooled air in the desired direction. Said Venetian blind may constitute a series of blades 46 pivoted at one end on brackets 47 secured to the side walls 48 of the box 35. A rod 48a passes through perforations 49 in the said slats or blades 46 and enlargements or bosses 50 provide rests for the blades 46. The upper portion of the rod 48 may be threadedly engaged by a boss 51 at the top of the forward end of the box 35. By manipulating a hand wheel 52 at the bottom of the rod 48, the blades 46 may be operated to assume any desired position to direct the flow of the cooled air passing between the radiator pipes and coil turns.

From the foregoing, it will be seen that the air cooling device of the present invention is extremely simple and inexpensive in construction, yet highly effective in operation.

It is apparent that the illustration shown above has been given by way of illustration and not by way of limitation and that the above described illustration is subject to wide variations and modifications, without departing from the scope or intent of the present invention. All of such variations and modifications are to be included within the scope of the present invention.

For instance, the hose 16 may be connected to a source of hot water, and then the apparatus may be used for supplying heated air to the room in order to raise room temperature during cold weather and thus serve as a heating unit.

What is claimed is:

An unrefrigerated air cooling device comprising in combination a box-like structure enclosing an air chamber and having an open side in communication with the outer atmosphere, a blind covering said open side and located in front of said air chamber, a radiator comprising a tubular frame substantially enclosing said open side and located adjacent to said blind, a series of parallel spaced apart tubes interconnected with said frame and extending across said open side, a helical frusto conical coil connected at its greatest diameter to the radiator frame and terminating at its smallest diameter in an outlet pipe at 20 an inner wall of said air chamber, said coil being located within said air chamber, a water inlet tube on the radiator adapted to be secured to a source of water supply to provide continuous water circulation through the radiator, a support 25 enclosing a chamber communicating with said air chamber, and a fan carried by said support in the last mentioned chamber to drive air through said chambers and expel same through the spaces between the water tubes in the radiator.
